MACHINE FOR APPLYING BUTTONS TO
AEROSOL CANSClifford A. Haumiller, 145 S. Liberty, Elgin, Ill.
Filed May 17, 1961, Ser. No. 110,703
4 Claims. (Cl. 29—208)

My invention relates in general to a machine for applying buttons to aerosol cans and more specifically to a machine into which are fed a series of cans having an opening in the top thereof, and into which are also fed a supply of buttons or tops having projections which fit the openings in the tops of the cans. The buttons are brought into proper alignment with the cans and then sufficient pressure is applied to force the projections into the openings and secure the same thereto.

Many types of so-called aerosol containers are on the market containing various liquids under pressure with a valve in the top of the container and with a push button controlling the valve to release the liquid in the form of a spray. In the past, most of the push buttons have been applied to such container valves by hand as only a certain amount of pressure must be applied to the buttons to press the pin into the opening of the valve securely without operating the valve to release the spray from the can.

It is therefore the object of my invention to provide a novel and simple machine to which the filled aerosol cans and the buttons to be applied thereto are both automatically fed and in which there is means for aligning each can with a button to be applied thereto and for causing a hammer to strike the button with just sufficient force to drive the pin on the button into the opening in the valve on the can without the valve.

Having described the general aspects of the invention I will now describe the same in detail with reference to the accompanying drawings in which:

FIG. 1 is a side view of the main shaft of the machine with the various elements assembled thereon and with certain other parts related thereto but not mounted thereon.

FIGS. 2-7 are top views of the various elements shown in FIG. 1 and will be later explained in detail.

FIG. 8 is a diagrammatic view taken from above the machine and illustrating the timing of the operations as the containers move around in a circle in the machine.

FIG. 9 is another straight line diagram illustrating again the timing of the various operations to align the buttons and the cans and force the pins on the buttons into the valve openings in the cans.

Referring now to FIG. 1, I have shown a shaft 2 which may be journaled in bearings either at top and bottom or as indicated in plate 3. A power driven pulley 4 is continuously rotated around the shaft without moving same until the magnetic clutch 5 is operated to link the shaft with the power pulley and cause rotation thereof as long as clutch 5 is energized.

At 6 I have shown a conveyor belt which feeds the aerosol cans 7 into the machine and from which the cans are picked up by the star wheel cams 8 and 9 the shape of both of which is clearly shown in FIG. 6. At 10 I have shown the cam race over which the cans are carried by star wheels 8 and 9 and which has a cam surface 10a which raises the cans as indicated in FIG. 9. The cam race 10 is supported in any desired manner by brackets such as 10b (FIG. 7) and does not rotate with shaft 2.

Also rigid with shaft 2 and rotating therewith is a valve locator disc 11, shown also in FIG. 5 with locating openings 11a into which the upper reduced valve portion of cans 7 is raised as the cans ride up on cam

2

surface 10a. Above the disc 11 and mounted by brackets 12a as indicated in FIG. 4 so that it is stationary is a button race 12 having a slot 12b into which a continuous series of buttons 13 are fed from a trough or supply slot in a member 14. The button race 12 has a cam 15 rigid therewith as shown in FIG. 4 which raises the punches 17a as will be described. In the diagram of FIG. 9 the cam 15 is shown separate from button race 12 in order to simplify the diagram. Mounted rigid with the shaft 2 and just above the button race 12 is a button hook disc 16 having a series of button hooks 16a each of which engages one of the buttons 13 as they enter the cam slot 12b as shown in FIG. 9 and carries the engaged button along slot 12b to point 12c (FIG. 4) where the shoulders of buttons 13 ride down a declining surface in the slot to a point where the lower pin portions of buttons 13 engage the holes in the top of a can such as at 7a (FIG. 9).

Also rigid with shaft 2 and just above the disc 16 is a punch holder 17 carrying a series of six punches 17a loosely inserted in holes equally spaced around its outer edge. Also mounted on the punch holder 17 is a cam ring 17b with a series of six cam surfaces for lifting and dropping a hammer 18, shown only in FIGURES 8 and 9. The cam ring 17 is secured to the upper disc surface of punch holder 17 by means of two or more brackets such as 17c which support the cam ring at a point above the cam 15 so as not to interfere with the lifting of the punches 17a by said cam 15.

At 18 and 19 in FIG. 1, I have shown a pair of electrical switches which jointly control the magnetic clutch 5 in a manner which will be described more in detail at a later point. The switch 18c is operated whenever a can is first picked up by wheels 8 and 9 to start rotation of shaft 2 and switch 19 is operated by a stop and dwell cam 20 to maintain the clutch energized until a second can is picked up to again operate switch 18c. The switches 18c and 19 are mounted on stationary brackets (not shown) and cam 20 is rigid with and rotates with the shaft 2.

Above the cam ring 17b is a hammer 18 shown only in FIGS. 8 and 9. The hammer is pivoted outside the periphery of ring 17 at a point 18a to a stationary bracket (not shown) and carries a hammer at its inner end of approximately two pounds in weight. The arm of the hammer rides over the cam surfaces 17b so that the hammer drops periodically onto a punch 17a which drives the button 13, which is aligned under such punch, into the opening of the container also aligned therewith.

Having described the general mechanical construction I will now describe the sequence of operations with reference to the diagrams of FIGURES 8 and 9. Referring to FIG. 8, as a can 7 is deflected into the path of star wheels 8 and 9 by a baffle plate such as 6a, it engages the switch 18c to energize the magnetic clutch 5 and cause it to rotate at a regulated speed with the power driven pulley 4. As soon as shaft 2 starts to rotate, the operating element of switch 19 rides up on a tooth of cam 20 to hold the clutch energized until said element drops into the next groove between the teeth. Thus as long as cans continue to be fed to star wheels 8 and 9 the shaft 2 continues to rotate. As the shaft 2 continues to rotate, the containers are carried along over can race 10 to the point where they are each lifted by cam surface 10a. The button hook disc 16 rotates also to a point where the buttons 13 are fed into slot 12b and at this point one of the hooks 16a picks up a single button 13 and carries it along to a point where the shoulder of the button glides down the downward sloping slot at 12c. At the same time one of the punches 17a is carried along by disc 17 and its outer edge 17d engages and rides along the cam surface 15 of plate 12.

This raises the punch 17a to a point above the button 13 which is being carried along directly underneath it and allows the raised punch to drop down and rest on the top of such button till it reaches the point directly under the hammer 18. The cans are kept in the proper path by a guide ring 6b which is stationary and whose mounting is also not shown. During this same period of rotation, the hammer 18 is lifted by one of the cam surfaces 17b from which it will be later dropped on the top of the punch 17a. Thus it will be seen that when a container 7 has reached the point corresponding to that of the left hand container of FIG. 9, one of the buttons 13 will be dropped down inclined surface 12c in alignment with the opening 7a in the top of the raised container, a punch 17a will be resting on the top of such button 13 at the same time the arm of hammer 18 will ride over the edge of cam surface 17b and the hammer will drop on top of such punch 17a to strike a sufficiently heavy blow to drive the pin on the lower end of such button 13 into the opening 7a to cause a tight drive fit of such pin into such opening without operating the release valve of the container. As previously stated the container as it is raised, enters one of the openings 11a so that all elements are properly aligned when the hammer strikes the punch. After the buttons have thus been applied to the cans, they are carried on around the circle until they are again carried away by conveyor belt 6.

Having fully described and ascertained the various features and aspects of my invention, what I consider to be novel and desire to have protected by Letters Patent will be pointed out in the appended claims.

What I claim is:

1. In a machine for attaching operating buttons to the valve operating mechanism of aerosol cans, a shaft carrying a series of rotatable discs, means for rotating said shaft to thereby rotate said discs, one of said discs having teeth for picking up aerosol cans from a source of supply, another disc having teeth for picking up the buttons from a source of supply, a third disc having alignment openings for the tops of said cans, a fourth disc carrying a series of vertically movable plungers, a hammer mounted adjacent an assembly point in the rotation of said discs, a sawtooth cam surface carried by said shaft and operative in the rotation thereof to raise and drop said hammer, a pair of cam surfaces rigidly mounted adjacent said discs, one of said surfaces operative to elevate a can into an opening in said alignment disc, the other of said pair of cam surfaces effective to elevate one of said plungers above the aligned can and a button therefor, said sawtooth cam effective in the assembly position to drop said hammer on the plunger to force the button onto the operate mechanism of the valve by means of the force of the blow.

2. A machine for attaching operating buttons to the valve operating mechanism in the top of aerosol cans containing liquid under pressure, comprising a disc for moving cans from an intake to an assembly position, another disc containing a series of alignment holes for centering the cans when in assembly position, a third disc for carrying the buttons from an intake to the assembly position, a fourth disc carrying plungers poised above each alignment opening, a hammer pivoted adjacent the assembly position, said hammer having insufficient weight to operate the valve of a can when resting thereon but sufficient weight to secure a button to the valve operating mechanism when dropped thereon, a sawtooth cam for intermittently raising and dropping said hammer at said assembly position, and means for rotating said discs and sawtooth cam to bring a can and button into said assembly position with a plunger poised above the button and then drop the hammer to wedge the button on the operate mechanism by striking the plunger with sufficient force to effect said assembly without operating the valve.

3. A machine such as claimed in claim 2 in which the rotation of said discs causes a can to be raised into an alignment opening in the assembly position while the button is lowered into engagement with the valve operating mechanism of the can, one of the plungers is raised and lowered on top of said lowered button, and the hammer is dropped onto the plunger to wedge the button onto said operate mechanism.

4. In a machine for applying operating buttons to the operating valve of an aerosol can in which liquid under pressure is released by the operation of the valve, a pin in one and an opening in the other of the button and valve for force fitting the two together, means in the machine for rotating a series of discs and cams by means of which a can and a button are each drawn from a source of supply to an assembly point and at which point there is means for raising the can and lowering the button to alignment and engagement, a hammer, a sawtooth cam rotated by the machine to raise the hammer and drop it on the aligned button at the assembly point, the force of the hammer when dropped on said button being sufficient to force drive the pin into the opening to assemble the button on the can.
